UNITED STATES PATENT OFFICE

2,604,139

FLARING TOOL

George E. Franck, Riverside, Ill., assignor to The Imperial Brass Manufacturing Company, a corporation of Illinois

Application March 31, 1950, Serial No. 153,149

8 Claims. (Cl. 153—81)

1

This invention relates generally to a tube working tool and more particularly to a tool for forming and burnishing a flare on tubing.

The general object of the invention is to provide a new and improved tube working tool and more particularly one adapted to perform both a flaring and burnishing operation.

Another object of the invention is the provision of means permitting a selective operation of the tool to perform either flaring or burnishing of a tube.

Another object is the provision of a tool having means first advancing a flaring cone toward a tube held in proper position to flare the tube and then means for disengaging the advancement of the cone to allow a burnishing operation to be performed.

Another object is the provision of a tube working tool having means permitting a slight advance of the flaring cone into the flare following the flaring operation and during the first portion of the burnishing operation.

Other objects and advantages will be apparent from the following detailed description taken in connection with the accompanying drawings, in which:

Fig. 1 is a side elevational view of the tube working tool of this invention, partly in section, and showing a tube held in operative position in dotted lines;

Fig. 2 is an enlarged, diametrical sectional view taken substantially along line 2—2 in Fig. 1;

Fig. 3 is an enlarged transverse section taken substantially along line 3—3 in Fig. 1;

Fig. 4 is an enlarged irregular section taken partially diametrically and partially through the detent means at right angles to Fig. 2.

While I have shown and shall hereafter describe one embodiment of the invention, it is to be understood that it is capable of many modifications. Changes, therefore, in the construction and arrangement may be made without departing from the spirit and scope of the invention as defined in the appended claims.

In systems or mechanisms wherein thin walled tubing is employed as, for example, refrigeration, controls, automotive, air craft, etc., a piece of tubing is coupled to some device such as a coolant coil, a carburetor or to another piece of tubing by means, commonly referred to in the trade as, a fitting. In order that the tubing may be securely fastened in fluid tight relationship, as well as, to be restrained against pulling out of the fitting, the end of the tube is usually flared outwardly after one part of the fitting has been

slipped over the tube. This flaring of the end of a tube is usually performed by a workman in the field requiring the employment of a hand flaring tool.

Referring now to the drawings, the tube working tool comprises a yoke 10 open at the end 11 and having inwardly projecting ledges 12 and 12a for grasping a tube clamping member 13 shown in dotted lines in Fig. 1. In well known manner, a tube 14 to be flared is clamped in position in the tube clamping member 13 after which the yoke 10 is placed astraddle the clamping member 13 in axial alignment with the tube. When in this position, the tool is properly placed to perform a flaring operation on the end of the tube 14. A flare 15 (as shown in dotted lines in Fig. 1) may be formed.

The flaring operation is performed by a flaring cone 20 fast on the end of a member here shown 20 as a stem 21 projecting rotatably through the closed or joined end of the yoke 10. Secured to the projecting end of the stem 21 is a handle 22 by means of which the stem and the cone may be rotated. Preferably the cone carries a plurality of rollers 23 (herein three) in appropriately formed recesses extending from the apex to the base of the cone in the conical surface thereof. The rollers 23 are retained rotatably in the recesses by swaging the margins of the recesses inwardly near the ends of the recesses so as to make the recesses at those points smaller than the diameter of the rollers. As an aid to retaining the rollers, there is provided an annular ring 24 generally L-shaped in cross section adapted to be mounted in surrounding relation to the base of the cone with a longitudinally extending flange 24a circumscribing the periphery of the cone base. The ring is held against rotation relative to the cone by means of a finger 25 struck out of a flange portion 24b and into a recess 26 formed in the cone base for that purpose.

Means is provided herein for advancing the cone as an incident to rotation thereof in order to adapt it to make the flare and for permitting the cone to be rotated without advancement to permit of a rolling or burnishing operation whereby the flared portion has removed from it any slight marks or irregularities that might otherwise prevent the formation of an absolutely fluid-tight joint. To that end, the stem 21 is adapted to be clutched to or disengaged from a second member which also projects rotatably through the closed end of the yoke concentrically with the stem. Mating sets of threads are provided, one set formed on one of said members

which is longitudinally movable relative to the yoke, and the other set being longitudinally stationary with respect to the yoke so that, depending upon the relative rotation of the sets of threads, the cone is rotated and advanced or retracted, or rotated without advancement. Herein this member takes the form of a tubular sleeve 27 having external threads 28, constituting the longitudinally movable set, formed over the major portion thereof and terminating in a head 29 having a diameter slightly larger than that of the base of the cone. The longitudinally stationary set of threads is herein formed in the yoke 10 with the sleeve member 27 extending threadedly therethrough. At its outer or projecting end the sleeve carries a ring 30 for limiting inward movement. The head of the sleeve is provided with an annular external recess for the reception of the radial flange portion 24b of the ring 24 and with an internal recess 31 for the reception of a bushing 45 nonrotatably secured to the stem 21 by means of a diametrical pin 47, the function of the latter being more fully described hereinafter. The sleeve 27 is hollow and a stem 21 extends coaxially through the sleeve and is rotatable therein. The stem and sleeve are so arranged to position the upper surface 33 of the cone 20 against the lower inner end surface 34 of the enlarged portion of the sleeve. These surfaces 33 and 34 are generally in frictional engagement and are always so arranged when any load or force is exerted against the rollers 23 of the cone 20.

In performing the flaring operation, the flaring cone is advanced toward the tube while rotating the cone. During this operation, means is provided for locking the stem 21, which is integral with the cone 20, to the sleeve 27 in order that the threaded portion 28 may feed the cone toward the tube. Herein this means takes the form of a catch member 43 selectively engageable to lock the stem and sleeve together. As best seen in Fig. 2, the enlarged portion 29 of the sleeve has a bore 40 extending transversely therethrough normal to the axis of the sleeve. The bore 40 extends to within a short distance of the opposite side of the portion 29 leaving a small annular ring 41 having an opening 42 therein smaller in size than the bore 40. The catch member 43 is positioned in the bore 40 to lock the stem 21 and sleeve together. To perform this function, a bushing 45 of generally cylindrical shape and having a longitudinal slot 46 in one side thereof is fastened to the stem 21, as by means of pin 47. The catch member 43 is provided with a detent 48 conforming in configuration with the slot 46 in the bushing 45. The detent 48 is carried by a generally cylindrical body portion 50 having an annular collar 51 adjacent the detent and a finger button 52 pinned to the outer end of the body portion. A helical spring 53 is compressed between the annular ring 51 and the ring 41 to urge the detent toward the bushing. The button 52 is arranged with its long dimension extending in the direction of the long dimension of the detent 48 to give a visible indication of the position of the detent. When the detent 48 is positioned in the slot 46 in the bushing 45, the sleeve and stem are securely locked together and the button 52 will clear the legs of the yoke 10 when the handle 22 is turned to advance the cone toward the tube. When, however, detent 48 is positioned outside and crosswise of the slot 46 the sleeve and stem are freed for rotational movement, one with respect to the other but the but-

ton 52 now will strike the legs of the yoke 10 and thus hold the sleeve against rotation relative to the yoke.

In the operation of the tube working tool, the stem and sleeve are first locked together by positioning the detent in the slot. The handle 22 is then turned sufficiently to advance the cone 20 into the end of a tube to perform the flaring operation. Since each revolution of the flaring cone also advances the cone into the tube, the particular stopping point may leave a slight depression in the flared end of the tube where the rollers 23 stopped. In order to eliminate any such irregularities left by the rollers 23, a burnishing operation is next performed. Herein this burnishing operation consists of a very slight advance of the cone followed by rotation of the cone without any axial advance.

To effect this burnishing operation, the operator grasps the button 52 and pulls the detent out of the slot 46 rotating it about the axis of the catch to turn the detent across the slot, as shown in dotted lines in Fig. 4. The handle 22 is then turned in the same direction as during the flaring operation. Due to the frictional forces that exist between the stem and the sleeve, as for example between the surfaces 33 and 34, the sleeve is caused to rotate with the stem until the button 52 strikes one of the legs of the yoke 10. This slight rotational movement of the sleeve advances the flaring cone into the tube just a slight distance to compensate for any backing off of the cone that may have accidentally occurred during the pulling out of the catch member 43, and also to be certain that the subsequent burnishing is at a depth to be effective to remove any and all markings that may have been made by the rollers.

With the catch member 43 now holding the sleeve against rotation relative to the yoke, continued rotation of the stem will rotate the cone without any advancement thereof. Thus the cone now irons out any irregularities in the flared portion of the tube.

After the operator has burnished the flare, making it perfectly round, he may back the handle in the opposite direction and turn the button 52 to align the detent 48 with the slot 46. After the sleeve and stem are again in locked position, the flaring cone may be backed out of the tube and another tube inserted in the clamping block 13 to perform a subsequent repeat operation.

I claim as my invention:

1. A tube working tool comprising, a yoke, a sleeve having a portion threadably received in the closed end of the yoke and an enlarged portion on its inner end, a stem extending coaxially through the sleeve and rotatable therein, a flaring element on the inner end of the stem and having a surface frictionally engaging the inner end of said sleeve, a handle mounted on the outer end of the stem and a spring pressed catch member mounted in said enlarged portion of the sleeve and selectively engageable with the stem to lock the sleeve and stem together.

2. A tube working tool comprising, a yoke, a sleeve having an outer portion threadably received in the closed end of the yoke and an inner enlarged portion, a stem extending coaxially through the sleeve and rotatable therein, a flaring cone on the inner end of said stem and having a surface frictionally engaging the inner end of the sleeve, a handle on the outer end of the stem for turning the stem, a bushing secured to said

stem adjacent the flaring cone and having a longitudinal slot in one side thereof and a catch means mounted in the enlarged portion of said sleeve selectively movable to a position in said slot to lock the stem and sleeve together.

3. Apparatus of the character described in claim 2 in which said catch means comprises a cylindrical body portion, a substantially rectangular detent on the inner end of the body portion adapted to enter the slot in said bushing and a button on the outer end of the body portion for manual selective positioning of the detent in said slot, said button extending outwardly to abut the yoke when the detent is out of said slot. 10

4. Apparatus of the character described in claim 2 in which a plurality of rollers are positioned in the face of said cone and an annular collar is positioned about the base of the cone partially between said cone and the inner end of the sleeve to retain said rollers in proper position on the cone face. 15 20

5. A tube working tool comprising, a yoke, a sleeve having an outer portion threadably received in the closed end of the yoke and an inner enlarged portion, a stem extending coaxially 25 through the sleeve and having a flaring cone on its inner end, and detent means positioned in said enlarged portion selectively engageable with said stem to lock the sleeve and stem together, said detent means having a finger actuated button 30 for selective manual placement of the detent means in and out of locking position, said button being adapted to strike a portion of the yoke to hold the sleeve against rotation with the stem when out of locking position and to clear the 35 yoke when in position locking the sleeve and stem together.

6. A tube flaring and burnishing tool comprising a yoke, a sleeve having an outer portion threadably received in the closed end of the yoke and an inner enlarged portion, a stem extending coaxially through the sleeve and rotatable therein, a flaring cone on the inner end of said stem having a surface frictionally engaging the inner end surface of said enlarged portion of the sleeve, a bushing secured to said stem immediately above said cone and within the enlarged portion of the sleeve, said bushing being generally cylindrical with a longitudinal slot in one side, a catch member mounted in said enlarged portion and having a detent on its inner end corresponding in configuration with said slot, a spring about said catch member urging the detent toward said bushing and a button on the outer end of the catch member for rotating said member about its axis to align said detent with said slot, said sleeve and stem being locked together when the

detent is positioned in said slot and being movable together by said frictionally engaging surfaces and by friction of the detent against the bushing when the detent is moved out of the slot, said button being adapted to abut the yoke to permit movement of the stem relative to the sleeve when the detent is out of locking engagement with the bushing.

7. A tube flaring tool comprising a yoke, a sleeve threadably mounted in the closed end of the yoke, a stem extending coaxially through the sleeve and rotatable therein, a flaring cone on the inner end of said stem, a plurality of rollers positioned in recesses on the conical surface of the cone, said recesses having side portions spaced apart a distance less than the diameter of the rollers, an annular collar about the base of the cone between the cone and sleeve to retain the rollers on the cone and a detent means mounted in the sleeve selectively engageable with the stem to lock the stem and sleeve together.

8. A tube working tool comprising a yoke, a pair of members including a sleeve rotatable in the closed end of the yoke and a stem extending coaxially through the sleeve and rotatable therein, a flaring element on the inner end of the stem and having a surface bearing against the inner end of the sleeve, said stem having a manually operable portion for turning the stem and flaring element about the axis of the stem, mating sets of threads with one of the sets on one of said members longitudinally movable with respect to the yoke and the other set being longitudinally stationary with respect to the yoke whereby said threads may advance the stem for performing a flaring operation, and a catch on one of said members selectively movable to one position positively to lock the stem and sleeve for joint rotation and movable to another position for releasing the members and engaging the yoke for holding the sleeve against rotation when relative rotation between said members is desired.
